UNITED STATES PATENT OFFICE

WESLEY SIDERS, OF FREMONT, NEBRASKA

MUFFLER FOR AUTOMOBILE ENGINES

Application filed November 5, 1925. Serial No. 67,135.

The present invention relates to mufflers, primarily intended for use in connection with internal combustion engines forming the motive power for automotive vehicles.

5 The primary object of the invention is to provide an improved muffler for internal combustion engines of automotive vehicles, which will not only act for silencing the explosive charges from the engine, but will also 10 prevent to a high degree of certainty, the accumulation of unfired charges from the engine within the muffler; such accumulation of unfired charges being due to various well known reasons, and when ignited by an 15 exploding charge from the engine quite frequently results in serious injury to the muffler and sometimes to the engine.

A further object of the invention is to provide an improved muffler embodying features 20 whereby large incandescent pieces of carbon blown from the cylinders of the engine into the muffler, will be effectively broken into minute particles for quickly extinguishing of the carbon and permitting ready passage 25 of the burning carbon from the muffler, and thus eliminate possibility of a large incandescent piece of carbon being allowed to remain in the muffler for possible igniting of a subsequent unfired charge entering the 30 muffler from the engine.

A still further object of the invention is to provide an improved muffler of this character which is extremely simple in construction, and which mufflers may be easily applied to 35 the exhaust pipes of existing types of vehicles.

Other objects and advantages of the invention will be apparent during the course of the 40 following detailed description, taken in connection with the accompanying drawing, forming a part of this specification, and in which drawing:—

Figure 1 is a central longitudinal sectional view through a muffler constructed in accordance with my invention;

Figure 2 is a rear end elevation of the same; and,

Figure 3 is a view illustrating the muffler 50 as applied to the exhaust pipe of an inter-

nal combustion engine forming the motive power for an automotive vehicle.

Referring to the drawing in detail, and wherein similar reference characters designate corresponding parts throughout the 55 several views; the letter A designates generally an automotive vehicle of usual construction, propelled by the usual internal combustion engine B. Extending rearwardly from the engine B and in a direction parallel with 60 the path of travel of the vehicle, is an exhaust pipe C to the rear end of which is attached the improved muffler D into which the exhaust charges of the engine B are directed as through the exhaust pipe C. 65

The improved muffler is formed with an internally threaded nipple or sleeve portion 5 which is intended for threaded connection in axial alignment to the rear end of the exhaust pipe C. Formed at the normally rear 70 end of this sleeve 5, and axially of the sleeve, is a rearwardly flaring hemispherical shell portion 6 forming an expansion chamber 7 into which the exhaust charges from the engine B are directed. Closing the rear larger 75 end of the hemispherical shell portion 6, is a concavo-convex baffle plate 8 having its convex surface extending into the chamber 7. If desired, this baffle plate 8 may be formed integral with the shell 6 but in the 80 example shown is attached by means of an annular flange 9 which may be curled about an annular rib 10 formed at the rear end of the shell.

The baffle plate 8 is provided with a plurality of perforations 11 which may be struck in the plate in a direction from its concave side to the convex side thereof, thus forming a number of sharp inwardly projecting barbs or spikes 12 at the convex side of the plate, 90 and extending in a direction substantially parallel to the axis of the sleeve 5. While these barbs 12 have been shown as being formed by punching of the perforations 11, they may be in the form of spike like members attached to the baffle plate, or formed in any other suitable manner for accomplishing the object in view. 95

It will readily be apparent that these inwardly extending spikes 12 will effectively 100

break up any large portions of incandescent carbon which are forced against the baffle plate 8 by the exhaust charge from the engine, and render the carbon susceptible of being forced through the perforations 11 and not remain in the chamber 7 in an incandescent or extremely hot condition for possible ignition of a subsequent unfired exhaust charge from the engine.

10 Such special configuration of the hemispherical shell portion 6, and the concavo-convex baffle plate 8, is for the specific purpose of creating a vacuum at the rear of the muffler when the vehicle is moving forwardly 15 and traveling only by its own momentum, or as when the vehicle is coasting on a down grade. It is well known that upon coasting or drifting with the spark control mechanism in an off and retarded condition, that 20 quite an accumulation of unfired charges form in the muffler and which explode within the muffler from the heat of the exhaust charges from the engine when the spark is moved to an on position. With the special 25 construction of the improved muffler as shown, the vacuum created at the rear of the muffler will effectively act for drawing this accumulation of unfired charges from the muffler and thus eliminate possible injury 30 to the muffler or engine upon switching on of the ignition system.

From the foregoing description of this invention it will be apparent that an extremely simple and efficient muffler has been provided 35 which will not only act for silencing of the exhaust from the engine, but also embodies features for preventing "back firing" in the muffler of an internal combustion engine of an automotive vehicle.

40 Various changes may be made to the specific form of invention herein shown and described, without departing from the spirit of the invention or the scope of the claims.

I claim:

45 1. A muffler for internal combustion engines, comprising a tubular internally threaded sleeve portion for attachment to the exhaust pipe of the engine, a flaring shell portion of hemispherical formation, 50 formed at the rear end of the sleeve portion concentric with the sleeve, and a perforated baffle plate of concavo-convex formation, closing the rear larger end of the shell with its convex side extending into the shell and 55 spaced a substantial distance from the rear end of the sleeve for providing a relatively large unobstructed expansion chamber and having its outer concave face opening to the atmosphere.

60 2. A muffler for internal combustion engines, comprising a threaded sleeve portion for attachment to the exhaust pipe of the engine, a flaring shell portion formed at the rear end of the sleeve portion and forming 65 an enlarged unobstructed expansion cham-

ber communicating with the sleeve, a perforated concavo-convex baffle plate closing the larger rear end of the shell portion with its convexed surface inwardly of the shell and with the crown of the plate disposed 70 in alignment with the axis of the sleeve, and spurs projecting inwardly from the convex side of the plate in parallel alignment with the axis of the attaching sleeve.
